DESIGN FOR A PERMANENT HAIR WAVING MACHINE

Charles O. McIntosh, Des Moines, Iowa

Application August 10, 1935, Serial No. 58,064

Term of patent 3½ years

To all whom it may concern:

Be it known that I, Charles O. McIntosh, a citizen of the United States, residing in Des Moines, in the county of Polk and State of Iowa, have invented a new, original, and ornamental Design for a Permanent Hair Waving Machine, of which the following is a specification, reference being had to the accompanying drawing, forming a part thereof.

Fig. 1 is a front view of my permanent hair waving machine; Fig. 2 is a side view of my permanent hair waving machine; and Fig. 3 is a top plan view of my permanent hair waving machine, showing my new design.

I claim:

The ornamental design for a permanent hair waving machine substantially as shown.

CHARLES O. McINTOSH.
